UNITED STATES PATENT OFFICE.

DAVID M. FOWLER, OF TERRE HAUTE, INDIANA, ASSIGNOR OF ONE-HALF TO ROBERT H. CATON, OF TERRE HAUTE, INDIANA.

ADJUSTABLE TROLLEY-WHEEL FORK.

1,384,458.

Specification of Letters Patent. Patented July 12, 1921.

Application filed August 28, 1920. Serial No. 406,699.

To all whom it may concern:

Be it known that I, DAVID M. FOWLER, a citizen of the United States, residing at Terre Haute, in the county of Vigo and State of Indiana, have invented a new and useful Improvement in an Adjustable Trolley-Wheel Fork, of which the following is a full specification.

My invention relates to that class of trolley-wheel forks, which are used to mount and hold a trolley-wheel upon the end of trolley-poles, for street cars and the like; and the objects of the invention are, first, to provide a trolley-wheel fork which will automatically hold the wheel supported thereby, at all times in contact with the trolley-wire; second, to provide a device which will automatically engage and pass any obstruction such as a cross wire or switch and restore the trolley-wheel to the wire after passing such obstruction; third, to provide a device which will meet all obstructions and protect and restore to the trolley-wire the trolley-wheel carried thereby, whether the same be traveling forward or backward, without the necessity of reversing the trolley-pole upon which it is mounted; and fourth, to provide a device which will be economical in structure and at the same time substantial and of maximum life and which will insure a maximum of safety to the wiring system and the car equipment, and which will obviate the necessity of all extra equipment such as trolley-reclaimers and the like.

These objects I attain by means of the mechanism illustrated in the accompanying drawings, in which:

Figure 1, is a view of the side of the fork, and showing by dotted lines the various positions which the trolley-wheel may assume.

Fig. 2, is a front view of the device.

Similar letters of reference refer to similar parts throughout the several views.

The letter A indicates the fork, which consists of two side-plates a, adapted to receive between the same, the trolley-wheel b, and which extend downward and form a bifurcated shank c, the two arms of which are joined together at their lower ends in the form of a ferrule-like socket d, adapted to receive the extreme end of the trolley-pole e.

The side-plates a, are broadened and extend beyond the trolley wheel b upon each

side, as shown in Fig. 1. The letter f indicates a semi-circular orifice which is cut through each of said side-plates a, and an upwardly projecting bearing-plate g, integral with the side-plates, is perforated centrally and adapted to serve as a pivot-bearing for the adjustable lever h, hereinafter described. The letter i indicates a segment-like slot which extends from one side of each side-plate to the other side thereof, and having for its center of curvature, the center of the pivot j, of said lever h.

The adjustable lever h, consists of a flat plate m, which is perforated centrally to receive the pivot j, which projects therethrough from the bearing-plate g, and which is further perforated to receive the projecting ends of the axle n of the trolley-wheel b, said axle being supported thereby immediately above the pivot j.

The lever h extends downward and forms an arm n, which is perforated at the lower end to receive the end of a bolt o, which bolt extends transversely across the fork A, below the trolley-wheel and projects, at each end through the segment-like slots i of the side-plates a, and through the corresponding arms of the levers h, to which said bolt is attached by means of the nuts p. Suitable washers w are placed between the hubs of the trolley-wheel and the inner walls of the fork to provide proper spacing of the wheel.

The letter q indicates strong finger-like guides, which are integral projections from the upper end of the levers h, and are curved inwardly to a point immediately above the upper edge of the trolley-wheel, respectively, to prevent the trolley-wire from slipping between the wheel and the corresponding side-plate, and said guides are angled outwardly, respectively, and thereby form a wide V-shaped guide-way adapted to straddle the trolley-wire and guide the same into the trolley-wheel groove.

A bolt r passes through the fork a short distance below the bolt o and is adapted to anchor a strong spiral tension spring s, the other end of which is attached to the middle of the bolt o; and said spring serves to exert a tension upon said bolt o and thereby hold the guides q in their normal position and to hold the trolley-wheel in normal position against the trolley-wire u.

When the trolley-wheel strikes an obstruc-

tion like a cross wire or other object, it bears against such object and is thereby forced downwardly and revolved upon the pivot *j*, incidentally depressing the axle of the trolley-wheel through the arc of the semi-circular orifice *f*, thereby carrying the trolley-wheel below and past the obstruction. When the obstruction is safely passed the spring *s* restores the trolley-wheel to its normal position against the trolley-wire.

Inasmuch as the axle of the trolley-wheel and the bolt *o* which connects the two lower ends of the lever arms *n*, are free to move in either direction within their respective slots or orifices *f* and *i*, it is apparent that the trolley-wheel will so pass any obstruction equally well, when going either forward or backward.

The advantages claimed for my invention over similar devices used prior hereto consist, in the automatic depression and replacement of the trolley-wheel within the fork itself, when obstruction is met and the incidental avoidance of the depression and release of the trolley-pole, the avoidance of the necessity of reversing the trolley-pole when it is desired to reverse the direction of the car, and the economy and safety provided by the automatic adjustment of the trolley-wheel made possible.

Having described my invention, its structure, operation and advantages, what I claim as new and useful and desire to secure by Letters Patent, is:—

- 35 1. A trolley-wheel fork comprising two side-plates, a bifurcated shank and a ferrule-like socket, said side-plates being perforated by semi-circular slots or orifices, adapted to receive and guide the axle of the trolley-wheel and a bolt adapted to connect the guide-levers, respectively, bearing-plates integral with said side-plates and adapted to support pivots upon which a pair of guide-levers revolve, a guide-lever mounted 40 pivotally upon the outer side of each side-plate and adapted to receive and eccentrically guide the axle of a trolley-wheel suspended between said side-plates, a pair of 45 finger-like guides integral with and projecting upwardly from said guide-levers, re-

spectively, a pair of arms integral with and extending downwardly from said guide-levers, a bolt extending through semi-circular slots provided therefor in said side-plates and adapted to connect the lower ends of the said arms, a bolt passing through said bifurcated shank, a spiral-spring attached at either end to said bolts, respectively, all substantially as shown and described and for the purpose set forth. 60

2. A trolley-wheel fork comprising two side-plates, a bifurcated shank, a socket adapted to receive the end of a trolley-pole, a pair of rotating levers pivotally attached to the corresponding side-plates and adapted to support and eccentrically move the trolley-wheel, a pair of finger-like guides integral with and projecting upwardly from said levers, respectively, a bolt connected pair of arms integral with and pendent from said levers, a bolt mounted between said arms, a spring attached to said arm supported bolt, adapted to exert tension upon said bolt and arms and anchored to a bolt mounted in the lower portion of said fork, all substantially as shown and described and for the purposes set forth. 70

3. In an adjustable trolley-wheel fork, a pair of slotted side-plates, supported by a bifurcated shank and ferrule-like socket, a pair of movable guide-levers pivotally attached to said side-plates, bearings in said side-plates adapted to receive pivots attached to said guide-levers, bearings in said guide-levers, positioned above said pivots and adapted to support the axle of a trolley-wheel suspended therein, said guide-levers being adapted to move the trolley-wheel backward or forward in an eccentric manner, a pair of finger-like guides, projecting 80 V-shaped and upwardly from the ends of said guide-levers, a spiral-spring having operative connection with said guide-levers and anchored within said bifurcated shank, all substantially as shown and described and for the purposes set forth. 90

DAVID M. FOWLER.
